(57) **CLAIM**

The ornamental design for a latching grab hook, as shown and described.

DESCRIPTION

FIG. 1 is a side perspective view of the latching grab hook; FIG. 2 is a right side view of the latching grab hook of FIG. 1;

FIG. 3 is a left side view of the latching grab hook of FIG. 1;

FIG. 4 is a top view of the latching grab hook of FIG. 1; FIG. 5 is a bottom view of the latching grab hook of FIG. 1; FIG. 6 is a front view of the latching grab hook of FIG. 1; and,

FIG. 7 is a rear view of the latching grab hook of FIG. 1. The environment shown in broken lines is for illustrative purpose only and forms no part of the claimed design.
